THOMAS U. WHITE, OF CHICAGO, ILLINOIS, ASSIGNOR TO WESTINGHOUSE ELECTRIC & MANUFACTURING COMPANY, A CORPORATION OF PENNSYLVANIA

SUPERVISORY CONTROL SYSTEM

Application filed June 7, 1926. Serial No. 114,088.

My invention relates to signalling systems and more particularly to that class known as supervisory control.

An object of my invention is to provide a code distributor means for remotely selecting an apparatus unit for operation.

Another object of my invention is to provide means whereby a unit operable to a plurality of positions, remotely selected by a code combination of impulses is placed under direct control from the selecting station for operation to any one or all of its positions.

Another object of my invention is to provide means including a continuously rotating distributor for remotely selecting an apparatus unit by means of a code and thereafter selecting an indicating device by means of a code responsive to the remote selection.

Another object of my invention is to provide means for making first a remote selection of a unit by means of a code from an office, next making a code selection at the office of said remote selection, then operating the unit selected to any one of a plurality of positions and finally providing a supervisory indication by means of a code combination of impulses of said operation.

Another object of my invention is to provide synchronous rotating distributors for operating a code selecting and code operating supervisory control system.

Another object of my invention is to provide means in a synchronous distributor, code responsive, supervisory control system for remote metering.

There are other objects of my invention, which, together with foregoing, will appear in the specification which follows:

Among the various schemes heretofore proposed for remote selection in a supervisory control system is the code type. This method of selection lends itself particularly well to supervisory control by reason of the fact that each selection depends upon a combination of impulses of various characteristics.

The signalling line employed in supervisory control must necessarily be placed along power circuits and is, therefore, subjected to inductive surges. By making a selection dependent on a code combination of impulses,

the effect of these surges, which would probably never simulate any one of these complete combination of impulses, can be considerably minimized.

This, however, it is found, is still not sufficient to satisfy the unusual degree of accuracy required in supervisory control and it is necessary in addition to the protection obtained by code selection, to identify, at the office, the selection made at the remote station, after which the dispatcher obtains direct control of the selected unit. This direct control enables repeated opening and closing of the circuit breaker without further selection or release.

For a great many years now, telegraph systems have employed synchronously rotating distributors for transmitting combinations of impulses for remote selection. This arrangement has been found to be cheap as well as simple and reliable.

A very serious draw-back, however, in these telegraph systems as far as "supervisory control systems" are concerned is the indirect control, or, in fact, lack of any control of the final operation of the remotely selected unit. As noted above, in "supervisory control systems" it is imperative that after completing the selection the dispatcher be, not only informed of the selection, but also obtain full as well as direct control of the selected unit.

My invention, therefore, comprises in general synchronously rotating distributors at an office and station over which a code selection is made, followed by supervisory identification of the selection made. Direct and full control of the remote unit is then obtained from the office end. For still further protection, the selecting apparatus is normally maintained disconnected from the line connecting the stations.

Referring to the drawings.

Figures 1 and 2 disclose the apparatus and circuit arrangements at the office, and.

Figures 3 and 4 disclose the apparatus and circuit arrangements at the sub-station.

In practicing my invention, I provide an office, Figures 1 and 2 connected to a sub-station, Figures 3 and 4 connected by a control line 183 and supervisory line 269, a synchronizing line 268 and a common return line 100

267 with synchronously rotating control distributors 155 and 346, supervisory distributors 229 and 478 and synchronizing distributors 247 and 492. Relays 179, 211, 313 and 418 are under the control of distributors 155, 247, 346 and 478, respectively for switching the control and supervisory lines 183 and 269 from the selecting to final operating circuit after the completion of the selection.

Referring more particularly to Figure 1, the individual control keys 103 and 112 control circuit breakers at the remote point. The lamps 101, 102, 109, and 111 are individual supervisory indicators for the corresponding circuit breakers. An operate key 118 controls the operation of the selection unit and release key 124 is provided to restore the "set up" selection. Relays 131 and 132 are coding devices individual to the keys 103 and 112 for controlling the code to be transmitted. Relay 129, when energized, opens the original energizing circuit for code relays such as 131 and 132. Relays 133, 134, 135, 141, 142 and 146 are the "supervisory" relays. Relay 172 and relays 169 and 171 are the first and final selecting supervisory relays respectively and relay 168 functions to render other selection ineffective after the final selection. Relay 152, 153 is the receiving relay for the final selection and determines whether the relays 169 or 171 will be energized. Relay 169 switches the control line from the code transmitting to operating position. The distributor controls the transmission of the code.

Referring to Figure 2, distributor 229 receives supervisory signals from the remote station to distribute the impulses to the supervisory code selector relays 201 and 207. Relay 203 energizes to open the operating circuit of the windings 201 and 202 and relay 205, when energized, opens the energizing circuit of the windings 206 and 207. The relay 204 is the group selecting relay. Relay 208, 209 is the start relay functioning to prepare the selecting circuit. Relay 211 functions to switch the supervisory line from the selecting to the operating circuit and windings 212 and 213 comprise the line relay. The distributor 247 operates to maintain synchronism between the office and sub-station distributor and is under the control of relays 214 to 219.

Referring to Figure 3, the distributor 346 is the control receiver for distributing the code signals to the selector relays 307, 308 and 316, 318, 321, 323 and 325. Relay windings 309, 311, 301 and 302 are the start relays, which function to close the selecting circuits over the contacts of relay 312. The relays 305 and 306 render other selection inoperative after final selection. Relay 314 is the line-relay and relay 313 switches the control line from the selection to the operating circuit.

Referring to Figure 4, relays 402 and 403

are final selecting apparatus, the circuits of which are under the control of relay 401. Circuit breakers 431 and 435 are individual to keys 103 and 112, respectively. Relays 404 to 408 and relays 413 to 417 are individual to the circuit breakers 431 and 435, respectively for operating a circuit breaker responsive to a control operation and for initiating the transmission of supervisory impulses indicative of the operation of the circuit breaker individual thereto.

The distributor 478 is a supervisory code sender, for code impulses prepared by the energization of relays 411 and 412. Relay 418 switches the supervisory line from its selecting to its operating circuit. The distributor 492 functions in conjunction with distributor 247 for maintaining the distributors at the sub-station and the office in synchronism and is under the control of relays 422 to 427. The function of the remaining relays will be obvious from the detailed description of the organization which follows: For purposes of convenience all of the polar relays in the drawings have been disclosed, showing two windings in order to illustrate that current of one polarity will operate the armatures in one direction and current of opposite polarity will operate the armatures in the opposite direction. Although a single battery is disclosed at the office, and a single battery at the substation with circuits for all of the relays energized from these batteries in certain instances, relays have been shown as connected to batteries which appear to be other than the main station battery. It will be understood, of course, that actually the same battery is employed and that the connections shown are merely for purposes of convenience in preparing the drawings.

Having described the apparatus in the system, a brief description of the operation followed by a detailed description will be given. For this purpose it will be assumed that the dispatcher desires to close a circuit breaker, such as 431.

The dispatcher will first close the key individual to the circuit-breaker which he desires to operate. This will transmit a code through the distributor 155 of a predetermined combination of impulses. These impulses are transmitted over the control conductor 183 and operate the line relay 314 at the sub-station. The impulses are then relayed through the distributor 346 at the sub-station. Responsive to these control code impulses, relays are energized for making, first, a group and then a final selection.

Following the group and final selection, impulses are transmitted over the distributor 478 and supervisory line 269 to operate the supervisory receiver relay 212 at the office. The impulses are relayed through the supervisory receiver distributor 229 to make a group and final selection which as a result

illuminates a supervisory lamp giving the dispatcher an identification of the selection which has been completed at the remote station.

5 The dispatcher will now operate the key 118 to close either its upper or lower contacts depending upon the desired operation. Release key 124 functions to release the selection.

10 By operating another of the individual keys, a code will be transmitted to the substation to connect the metering device at the remote station to the receiving meter. All of the distributor brushes at the office are mounted for rotation on a single motor-driven shaft. Similarly the distributor brushes at the substation are mounted for rotation on a single motor-driven shaft.

15 Normally the distributor brushes at the office and the substation rotate in synchronism each being locally driven. Synchronism is maintained by means of the two distributor brushes 493 and 264. As the distributor brush 264 is passing over the first segment shown on the right hand half of the bank, an impulse is sent from the positive side of the battery 266 through the segment over which the brush 264 is at that moment passing and through brush wiper 264, the windings 218 and 219 synchronizing conductor 268, through the winding 422 and 423 of the polar relay through the brush 493 and the segment of the distributor and over common return conductor 267 to the midpoint of the battery 266.

20 As a result of the energization of the relay 219 over the circuit just traced, the armature 246 operates to close its right hand contact and a circuit is completed from the positive side of the battery 266 through the armature 246 and its right hand contact, the windings 217 and 216 to the mid point of battery 266. The relay windings 216 and 217 when energized move their armature 245 to withdraw the latch 270 integral therewith from the path of the distributor brush 264. Normally, with the relay deenergized, this projection is in the path of the brush and therefore acts to bring the brush to a stop.

25 Simultaneously at the remote station, the energization of the relay 422 over the circuit just traced completes a circuit from the positive side of the battery 477 through the left hand contact of the armature 474 and through the windings of relays 427 and 426 to the mid point of battery 477. The relay 426 and 427 operates to move its armature 476 and thereby withdraws the latch from the distributor arm 493. In this manner the brush arms 264 and 493 pass upon their first segment of the right half of their respective banks in synchronism.

30 The distributor arm 493 is arranged to rotate slightly faster than the arm 264 and will therefore reach the first segment on the right

hand half of the bank a little ahead of the distributor arm 264. In such a case it will be held by the latch from further rotation until the brush 264 reaches its first segment after which the two will rotate in synchronism. 70

When the distributor arm 264 leaves the segment 290, the circuit just traced over the synchronizing line from the positive side of battery 266 is opened. The brush 264 will now pass over the segment 291 and a circuit 75 similar to the one just traced over the synchronizing line is completed from the negative side of battery 266 and through the distributor 247 at the office and 492 at the substation including the line relays 218, 219, 422 80 and 423.

85 The relay winding 218 is energized over this circuit and operates the armature 246 to its left hand contact. As a result of this operation of armature 246, an obvious energizing circuit is completed for the relay windings 214 and 215 and the armature 244 is operated to remove the latch from the distributor brush 264.

90 Simultaneously with the energization of relays 218 and 219 the relay winding 423, at the substation end is energized over the circuit including the relay winding 218. The armature 474 is operated to close its right hand contact which in turn completes an 95 obvious energizing circuit for the relay windings 424 and 425. As a result of the energization of this relay, the armature 475 is operated to remove the latch from the distributor brush 493 which at this time is on segment 497. In this manner by the two reversals of polarity during each rotation of the distributor arms, two synchronizing impulses per revolution are transmitted to maintain the rotating brushes in synchronism. 100 105

110 Although the distributor brush 264 is the synchronizer and the brush 493 the synchronized, by arranging to latch and unlatch the distributor 264 as well as distributor brush 493, failure of an impulse over the line 268 for any reason whatsoever will prevent further rotation of the brush 264 as well as 493.

115 In actual operation the speed of the two brushes can be so arranged by means of the well developed modern synchronous motor as to make them so nearly alike that the latches 245 and 476 function in such a manner that neither brush is ever actually latched and brought to rest but continues on the contrary to rotate substantially continuously. 120

125 It is understood of course, that other arrangements for synchronism can be used.

130 In order to better understand the invention, the following detailed description thereof is given.

135 As in the brief description above, it will be assumed that the dispatcher desires to close the circuit-breaker 431. In order to accomplish this, he will close the individual key 103. This key is maintained in operative position 140

until released. As a result of this operation, a circuit is completed from the negative side of the battery 266, conductor 185, the winding of relay 131, upper contact and lever 105, the back contact, and armature 104 and conductor 186 to the mid point of battery 266. Relay 131 is energized over this circuit and completes a locking circuit for itself from the negative side of battery 266, conductor 185, winding of relay 131, its first closed contact, closed contact of key 124, conductor 186 to the midpoint of battery 266.

A further result of the energization of relay 131 is to prepare an energizing circuit for the relay 152 at the second contact and complete an energizing circuit for relay 129 from the negative side of battery 266, conductor 185, winding of relay 129, the second contact of relay 131, conductor 186 to the positive side of battery 266. Relay 129 is energized to open all the remaining energizing circuits of the code relays such as 132.

Another result of the energization of relay 131 is to complete an energizing circuit for the relay 148 from the negative side of battery 266, conductor 185, the winding of relay 148, the third contact of relay 131 to positive side of battery 266 over conductor 186.

The relay 148 energizes to impress a negative polarity from the battery 266 upon the control conductor 183 over armature 149 and its front contact when the wiper 156 reaches the contact 157. A further result of the energization of relay 148 is to open the releasing circuit at armature 151.

From the operations thus far described, it is evident that the code relay locks itself up over its first contact, closes the energizing circuit for relay 129 at its second contact, which, in turn, opens the energizing circuits of other code relays and completes an energizing circuit for relay 148 at its third contact, which prepares to impress a negative impulse or start impulse on the control line from armature 149 and opens a releasing circuit at armature 151.

The fourth and fifth contact of the code relay functions in a manner hereinafter to be described for transmitting the control code.

As already noted, when the distributor brush 156 reaches the contact 157, the energization of the relay 148 impresses a negative impulse on the control conductor 183 from the negative side of the battery 266 over conductor 185, the front contact and armature 149, contact 157, and wiper 156 of the distributor 155, back contact and armature 181, conductor 183, armature 359 and its back contact, windings 314 and 315, conductor 375, and common return conductor 267 to the positive side of battery 266.

The distributor brush 356 being in synchronism with brush 156, the power will be on contact 347 at this time and a circuit will be completed from the negative side of battery

477 over conductor 366, the right-hand contact and armature 339, the brush wiper 356 and contact 347 of the distributor 346, windings of start relays 304 and 303, conductor 381, and conductor 375 to the midpoint of battery 477. The start relay 303 is energized over this circuit to close the left-hand contact of armature 328 and a circuit is completed for the relay 312 from the negative side of battery 477, conductor 366, winding of relay 312, the left-hand contact and armature 328, conductor 381, and conductor 375, to the midpoint of battery 477.

The relay 312 energizes over this circuit and completes a locking circuit for itself from negative battery over the circuit just traced through the winding of relay 312, its first contact, back contact and armature 331, conductors 381 and 375 to the midpoint of battery 477 and prepares selecting circuits at its second to seventh contacts. By normally maintaining these selecting circuits open, line disturbances from any cause whatsoever have no effect on the selection when no code is being transmitted.

The distributor brush 156 at the office will now reach its contact 158 while at the same time the distributor brush 356 is passing over its contact 348 at the substation and a circuit is completed from the positive side of the battery 266 over conductor 184, the fourth contact of relay 131, contact 158 and brush wiper 156 of the distributor 155, back contact and armature 181, conductor 183, armature 359 and its back contact, winding of relays 314, 315, conductor 375 and over common return conductor 267 to the midpoint of battery 266. This is the first code impulse.

The line relay 314 is energized and operates its armature 339 to close its left-hand contact. As a result, a circuit is completed from the positive side of battery 477 over conductor 374, the left-hand contact and armature 339, the distributor brush 356, and contact 348 of the distributor 346, the second contact of the relay 312 and winding of relays 301 and 302, conductors 381 and 375 to the midpoint of battery 477.

The relay 301 is energized over this circuit to operate the armature 327, closing its left-hand contact and a circuit is completed from the negative side of battery 477 over conductor 366 through winding of group selecting relay 307, back contact and armature 332, left-hand contact and armature 327 and conductors 381 and 375 to the mid-point of battery 477. Relay 307, upon energization, completes a locking circuit for itself from negative side of battery, over conductor 366 through the winding of the relay 307, through its first contact, back contact and armature 329 and over conductors 381 and 375 to the midpoint of battery.

The relay 307 is the first or group selecting relay. The transmission of a negative im-

pulse over the control conductor 183 instead of the impulse just traced would have operated the line relay windings 314, 315 so as to transmit an impulse of opposite polarity to the relay windings 301 and 302 and the group selecting relay 308 instead of the selecting relay 307 would have become energized. By this arrangement, it is evident therefore that the first contact of the distributor can be used to make two group selections by the different polarities. One result of the energization of relay 307 is to complete an energizing circuit for the relay 306 from the negative side of battery 477 over conductor 366 through the winding of relay 306 the second contact of relay 307 over conductors 381 and 375 to the midpoint of battery 477. The energization of relay 306 opens all the group selecting circuits at its armatures 332 and 333.

The distributor brush 356 at the substation now passes on to its contact 349 in synchronism with the distributor brush 156 which is on the contact 159 at the office and a circuit is again completed from the positive side of battery 266, conductor 184, the fifth contact of the relay 131, contact 159, back contact and armature 181, conductor 183, armature 359 and its back contact, windings of relay 314, 315, through the common return conductor 267 over conductor 375. This is the second code impulse.

Relay 314 is again energized to close its left-hand contact and a circuit is again completed from the positive side of the battery 477 over conductor 374, the left-hand contact and armature 339, the distributor brush 356 and the contact 349 of the distributor 346, the third contact of relay 312 and the windings of relays 317 and 316 over conductor 367 and the first armature contact 439 of relay 401 to the midpoint of battery 477.

Relay 316 is energized and the armature 341 closes its left-hand contact. A circuit is therupon completed from the negative side of the battery 477, conductor 366, winding of the relay 402, conductor 362, the third contact of the relay 307, the left-hand contact and armature 341 to the midpoint of battery 477, over conductor 375. The relay 402 makes the final selection and completes a locking circuit for itself from the negative side of battery 477 over conductor 366, as traced, through the winding of relay 402 and its first contact, over conductor 364 back contact and armature 329 to the midpoint of the battery 477 over conductors 381 and 375.

A further result of the energization of relay 402 is to complete an energizing circuit for the relay 401 from the negative side of the battery 477, winding of relay 401, second contact of the relay 402 to the midpoint of the battery 477, a circuit for relay 419 extending from the negative side of battery 477, wind-

ing of relay 419, sixth contact of relay 402 and back to the midpoint of battery 477, and to prepare a locking circuit for relay 313 at its fourth contact.

The relay 401 is energized and opens the circuits of all the final selecting relays at its armature contacts, thereby preventing any further selection from being made.

In view of the fact that all of the selections have now been completed, no further operation takes place over the control lines, as the wiper 156 passes over the contacts 161 to 164 at the office in synchronism with the wiper 356, which passes over the contacts 351 to 354 at the substation.

The distributor brushes at the two stations, now rotating in synchronism reach their contact closers 166 and 358, respectively, simultaneously. As a result of the closing of contact 166 at the office, a circuit is completed from the negative side of the battery 266, conductor 185, through the winding of relay 179 over the closed contacts of lever 166 and over conductor 186 to the midpoint of battery 266. The relay 179 is energized and switches the line 183 from its selecting to its operating circuit. Similarly, at the substation, the relay 313 is energized from the negative side of battery 477 over conductor 366 through the winding of relay 313, the closed contact of the lever 358 to the midpoint of battery 477 over conductor 375. Relay 313 is locked over its front contact and armature 338, conductor 365, fourth contact of relay 402, armature 496 and its back contact to the midpoint of battery 477. The control conductor 183 is thus switched from the receiving selector to the operating circuit.

The energization of relay 179 prepares a locking circuit for itself at the front contact of armature 182. The locking circuit however is not effective at this time by reason of the fact that it is completed over the closed contacts of the supervisory selectors none of which have operated at this time and the relay becomes deenergized as soon as the wiper 156 passes to the contact 165. The energizing of relay 179 at this time therefore has no effect and the armature 181 again closes the selecting circuit over its back contact.

It will be recalled that upon the operation of the final selecting relay 402 at the substation, an energizing circuit was completed for the relay 419. When the distributor wiper 479 reaches the contact 481, the distributor wiper 239 at the office rotating in synchronism therewith will reach its contact 231. A circuit will now be complete from the negative side of battery 477 over the front contact and armature 467 the contact 481 and wiper 479, back contact and armature 472, conductor 269, armature 227 and its back contact and the winding of relays 212 and 213 and over the common return conductor 267 to the midpoint of battery 477.

The relay winding 212 will operate its armature 243 to close its left hand contact and an energizing circuit will thereupon be completed for the relay winding 201 and 202 from the negative side of battery 266, the left hand contact and armature 243, the distributor brush 239 and start contact 231 of the distributor 229, the relay windings 201 and 202 to the midpoint of the battery 266.

10 The relay winding 201 is energized over this circuit and closes an energizing circuit for the relay 204 from the negative side of battery 266, conductor 185, winding relay 204, the left hand front contact of armature 221 to the mid point of battery 266 over conductor 186.

15 The relay 204 is energized over this circuit and completes a locking circuit for itself from negative battery 266, over conductor 185, the winding of relay 204, the first contact of relay 204, the back contact and armature 222 to the midpoint of battery 266 over conductor 186. Over the remaining contacts circuits are prepared for the supervisory and identification selection.

20 The distributor wipers 239 and 479 operating in synchronism will now close their contacts 232 and 482 simultaneously with the result that a circuit will be completed from the positive side of the battery 477 through the first contact of the relay 307 over conductor 377, contact 482 and distributor brush 479, the back contact and armature 472, conductor 269, the armature 227 and its back contact, windings 212 and 213 to the common return conductor 267. The polarity of this impulse, it will be noted, is determined by the group selection made at the station and acts therefore as an identification thereof.

25 The relay winding 212 will again be energized over this circuit to close a circuit from the positive side of battery 266 in a manner already traced through the distributor brush 239 and contact 232, the second contact of relay 204, armature 224 and its back contact through the windings 206 and 207 to the midpoint of battery 266 over the conductor 186.

30 The relay winding 206 is energized over this circuit to complete an energizing circuit for the relay 172, from the negative side of battery 266, conductor 185 through the winding of relay 172, conductor 198, the left hand contact and armature 225 to the midpoint of the battery over conductor 186. Relay 172 is associated with the relay 307 and like the latter is the first or group selecting relay.

35 The energization of the relay 172 completes a locking circuit for itself from the negative side of battery 266, through the winding of relay 172 as already traced through its first contact and over conductor 187, back contact and armature 222 and conductor 186 to the midpoint of battery 266.

40 A further result of the energization of relay 172 is to complete an energizing circuit

for the relay 205 from the negative side of battery 266 over the conductor 185, conductor 197, the winding of relay 205, conductor 196, through the second contact of the relay 172 to the midpoint of the battery 266 over conductors 199 and 186. The final supervisory circuit is completed over the third contact of relay 172. The energization of the relay 205 opens all the group selecting circuits of which, for simplicity, only one is shown at 75 armature 224 thereby preventing any further group selection from taking place.

45 The distributor brushes 239 and 479 operating in synchronism now reach their respective contacts 233 and 483 simultaneously. A 80 circuit is now completed from the negative side of battery 477 through the contact 495 of relay 402 over the segment 483 and distributor brush 479, the back contact and armature 472, conductor 269, the armature 227 85 and its back contact, the windings of relays 212 and 213 in series to the midpoint of battery 477 over common return conductor 267. This impulse as in the previous case, is controlled by the selecting relay energized at the 90 substation and thus identifies the final selection.

50 The relay winding 212 is energized by this negative impulse and closes its armature 243 over its left hand contact. A circuit is now 95 completed from the negative side of battery 266 through left hand contact and armature 243, the distributor brush 239 and contact 233, conductor 188, winding 153 and 152 to the midpoint of battery 266 over conductor 186.

55 The relay winding 152 is engaged over this circuit and completes an energizing circuit for the final selecting relay 169 from the negative side of battery 266, conductor 185, the winding 169, the left hand contact and armature 154 to the midpoint of battery 266, over conductor 186.

60 The relay 169 energized over this circuit to make the final selection locks itself up over 100 its first contact from the negative side of battery 266 and through winding of relay 169 as already traced, its first contact, conductor 187 the back contact and armature 222 to the midpoint of the battery 266 over conductor 186. An energizing circuit is also completed for the relay 168 from the negative side of battery 266 over conductor 185, winding of relay 168, the second contact of the relay 169, conductor 193 to the midpoint of battery 266 110 over conductor 186 and a locking circuit is prepared for the relay 179 at the third contact of relay 169. A supervisory circuit is prepared for the relays 133 and 135 over the fourth contact of relay 169 and a circuit is closed for the identifying lamp 127 at the fifth contact from the negative side of battery 266, conductor 185, the lamp 127, the fifth contact of the relay 169, conductor 193 115 to the midpoint of the battery 266.

130

The dispatcher is thus apprised of the correct selection at the remote point and he may now with assurance close his operating key to perform the selection desired. The distributors at the two stations now rotate passing from contact to contact, but, no other selection can be performed since the relay 168 at the office holds open all selecting circuits at its contacts, and the relay 401 at the substation simultaneously holds open all its selecting circuits.

The brushes 156, 356, 479, and 239 rotating in synchronism will now reach and operate contact closers 166, 358, 489 and 242 respectively. The closing of the contact 166 completes an energizing circuit for the relay 179 from the negative side of battery 266, through the winding of relay 179, the contact of the closer 166 to the midpoint of battery 266 over conductor 186.

The relay 179 is energized and completes a locking circuit for itself over its armature contact 182 from the negative side of battery 266 through the winding of relay 179, as already traced, front contact and armature 182, the third contact of the relay 169 over the last contact of the relay 131 to the midpoint of the battery over conductor 186.

It will be noted that the final selection must agree with the code relay which is operated when completing a locking circuit for the relay 179 so that even if the dispatcher negligently fails to notice a false selection such a false identification received at the office would render the control operation ineffective.

As we pointed out above the relay 313 is at this time electrically locked at the substation its circuit being completed originally from the negative side of battery 477, conductors 402 and 366, winding of relay 313, the contact of the latch 358 to the midpoint of battery 477, over conductor 375. The locking circuit for the relay 313 is completed over the circuit from the negative side of battery 477 over conductor 366, as already traced, the winding of relay 313, front contact and armature 338, conductor 365, the fourth contact of the relay 402 armature 496 and its back contact to the mid point of battery 477. In a similar manner relay 418 is energized over the circuit from the negative side of battery 477, winding of relay 418, the contact 489, to the midpoint of battery 477 and completes a locking circuit for itself from the negative side of battery 477, relay 418, the front contact and armature 473, the front contact and armature 469 to the midpoint of battery 477.

At the office the relay 211 is energized over the circuit from the negative side of battery 266, through the winding of relay 211, the contact of the lever 242 to the midpoint of battery 266 and thereupon completes a locking circuit for itself from the negative side

of battery 266 through the winding of relay 211, the front contact and armature 228, conductor 194, the closed contact 174, the last contact of relay 131 to midpoint of the battery over conductor 186.

The selections at the office and substations having now been completed there is a direct connection from the operating key at the office to apparatus unit at the substation and a similar direct supervisory circuit from the apparatus unit to the individual lamps at the office. It will be noted that although the selection was made by the means of the code combination of impulses, that the finally selected apparatus unit and supervisory indicator are connected to their individual members over circuits cleared of any selecting apparatus.

The dispatcher thus having direct connection to the unit may either open or close the circuit breaker or repeatedly open and close the unit in succession if so desired. This feature is of a decided advantage as it enables metering in a code system.

Since it is assumed that the dispatcher desires to close the circuit breaker, a circuit will be completed from the positive side of battery 266, the conductor 184, the contacts 119 and 121 of the key 118 moved to its upper position, ring 113 brush 156, ring 114 the contact 107 and 108 of the individual key 103, the front contact and armature 181, control conductor 183, the armature 359 and its front contact, ring 342, brush 356, ring 343, conductor 499 winding of relay 491 to the midpoint of battery 266 over conductor 267. The armature 487 closes its right hand contact to complete an energizing circuit from the positive side of battery 477 to the right hand contact and armatures 487, conductor 498, third contact of relay 402, windings of relays 407 and 408 to the midpoint of battery 477.

The armature 449 is moved to close its right hand contact thus completing an energizing circuit for the solenoid 432 which functions to close the circuit breaker 431.

As the circuit breaker moves from its open to closed position, pallet switch 434 closes its contacts to complete an obvious energizing circuit for the relay 406 which in turn completes an energizing circuit for the relay 405, over armature 448 and its front contact. Upon the energization of relay 406 but before the energization of relay 405 a momentary circuit is completed for the relay 404 over contact 445 and armature 446 and its back contact and front contact and armature 477. Relay 404 energizes and completes a locking circuit for itself over armature 444 and its front contact and armature 452 and its back contact. A further result of the energization of the relay 404 is to complete an energizing circuit for the relay 411 from ground through battery,

winding of the relay 411, front contacts and armature of relay 404, back contact and armature of relay 413, and back contact and armature of relay 409 to ground. Relay 411 locks itself over its first contact and the back contact of relay 428. The relay 411, which is the supervisory code-transmitting relay individual to circuit breaker 431, will now transmit a code combination of impulses to the first station. Relay 411 is locked over a circuit including its first contact and back contact and armature 452 to ground.

An energizing circuit is completed for the relay 409 from positive side of battery 477 over the last contact of relay 411 winding of relay 409 to the mid-point of battery and an energizing circuit is completed for the relay 419 over the next to the last contact of relay 411 from the negative side of battery 477 through the winding of relay 419, through the contact of relay 411 to the midpoint of the battery. The second and third contacts of relay 411 function to transmit a supervisory code individual to the apparatus units that is operated. Since, however, in this case the selection has already been completed at the office, the code relay has no function as such at this time.

A supervisory impulse is, however, transmitted from the negative side of battery 477 through the upper winding of relay 428, the front contact and armature 451, the third contact of the relay 411, the back contact and armature 471, the front contact and armature 472, conductor 269, the front contact and armature 227, conductor 195, through the third contact of the relay 172 to fourth contact of relay 169, the armature 139 and its back contact winding of relay 135 to midpoint of battery 477 over common return conductor 267. Energization of relay 428, as a result of the transmission of supervisory signal, opens the locking circuits of relays 404 and 411. Relay 428, upon energization, opens the locking circuit of relay 411 traced above and this relay deenergizes.

The relay 135 is energized over this circuit and unlatches the armatures 136 and 137 by withdrawing latch armature 138.

An energizing circuit is completed for the relay 134 the negative side of battery 266, winding of relay 134, the back contact and armature 137 to the midpoint of battery 266 over conductor 186.

Normally with the circuit breaker open, as already shown, the lamp 101 was energized over the closed contact and armature 136 from the negative side of battery to the midpoint of battery 266 over conductor 186.

Upon the operation of relay 135, as already traced, the energized circuit for the lamp 101 is opened at armature 136 and a circuit closed for the lamp 102 thereby giving the dispatcher a supervisory indication of the operation of the circuit breaker from the open to the closed position.

The dispatcher may operate his release key 124 to restore the selection either before or after completing the control operation. Relay 131 becomes deenergized to in turn deenergize the relay 129 and relay 148. A further result of the deenergization of relay 131 is to open the locking circuits of the relays 168, 169 and 179.

Simultaneously with the opening of the release key contact 124, the contact 116 is closed. When the distributor brush 156 crosses the segments 117 a circuit is completed from the positive side of battery 266 through the closed contact 116 to segment 117 and brush 156, front contact and armature 181, conductor 183, front contact and armature 359, brush 356, segment 396 winding of relay 494 and over conductor 267 to the midpoint of battery 266. The code and selector relays are so designated that they are held energized for a short interval of time long enough to permit the distributor brush to reach the segment 117 so that the relay 179 is not yet deenergized at this time.

The energization of relay 494 operates its armature to open the locking circuit of the relay 313, which thereupon permits its armature to drop to its back position and as the brushes 156 and 356 now pass over the segments 165 and 355 a circuit is completed from the positive side of battery 266 over conductor 184 back contact and armature 151, the segment 165, brush wiper 156, back contact and armature 181, conductor 183, the armature 359 and its back contact, windings of relays 314 and 315 to the midpoint of battery 266 over conductor 375 and the common return line 267.

Relay 314 is energized and closes its left hand contact to complete a circuit from the positive side of battery 477, over conductor 374, the left hand contact and armature 339, through the distributor brush 356 and segment 355, windings of relays 311 and 309 to the midpoint of the battery 477 over conductor 381.

Relay 311 is energized to close armature 336 and its right hand contact. An energizing circuit is completed for the relay winding 305 from the negative side of the battery 477 over the conductor 366 through the winding of relay 305, the right hand contact and armature 336 to the midpoint of the battery 477 over conductor 381.

The relay winding 305 is energized to open the locking circuit of the selecting relays 307 and 402 at armature 329 and to open the locking circuit of the relay 312 at armature 331.

The deenergization of the relay 307 opens the energizing circuit of the relay 306. The deenergization of the relay 402 opens the energizing circuit of relay 401. In this manner all the selecting apparatus is restored to normal at the substation.

The deenergization of the relay 307 also opens the energizing circuit of the relay 421 which in turn opens the locking circuit of the relay 418.

5 As the distributor arm 479 reaches its segment 488 and distributor arm 239 reaches its segment 238, an impulse is transmitted from the positive side of battery 477 over the back contact and armature 468, back contact 10 and armature 466, distributor contact 488, the brush arm 479, back contact and armature 472, conductor 269, armature 227 and its back contact and the winding 213 to the midpoint of battery 477 over common return conductor 267. As a result of the 15 energization of the relay winding 213, the armature 243 closes its right hand contact and a circuit is completed from the positive side of battery 266, the right hand contact 20 and armature 243, distributor brush 239, segment 238, windings 208 and 209 to the midpoint of battery 266.

The energization of relay 209 operates armature 226 to close its right hand contact 25 and complete an energizing circuit for the relay 203 from the negative side of battery 266 over the conductor 185, the winding of relay 203, right hand armature contact 226 to the midpoint of battery 266. The relay 30 203 is energized to open the locking circuit of the relay 204. The deenergization of the relay 204 opens the energizing circuit of the relay 205. In this manner the apparatus is restored to normal.

35 Should an apparatus unit operate automatically at the substation end, the supervisory operations will be exactly the same as described in connection with a control 40 operation of the unit except that the code transmitted will be determined by the code relay energized such as 411 and 412 instead of by the selecting relays which have been closed. It will be noted that the code relays of all code circuits are multiplied with 45 those completed by the selecting units and will therefore function in the same manner. In brief, the operations which take place following an automatic operation of such a circuit breaker as 435 to its closed position, 50 is as follows: Relay 415 will energize to, in turn, complete an energizing circuit for the relay 414 which, however, does not energize before an energizing circuit is completed for the relay 413, which, in turn, locks itself up 55 over its own front contact. The energization of the relay 413 completes an energizing circuit for the supervisory code-transmitting relay 412 and, at the same time, opens the energizing circuits for all the other code 60 relays. As the distributor 479 now rotates, impulses will be transmitted over the supervisory line 269 to operate the windings 212 and 213 of the receiving supervisory relay. These supervisory impulses will then be 65 repeated through the distributor 229 to oper-

ate a group and final selecting relays which, in turn, upon energization, will make a selection of one of the supervisory receiving relays in a manner which has been described in detail above. When the supervisory code signals have been transmitted, a supervisory impulse will be transmitted from ground through battery, the upper winding of relay 499, the front contact and armature of relay 414 through the third contact of relay 412, the back contact and armature 477, the front contact and armature 472, over the supervisory line 269 and through the contacts of the selectors energized to the individual supervisory relay which, upon energization, will illuminate the proper lamp in the manner which has been described in detail above. It should be noted that after the selection of the apparatus unit by a predetermined code combination of impulses the unit may be operated to its plurality of positions without any further selection; that is, after the circuit breaker has been selected the dispatcher may move his key to open and close the circuit breaker successively as often as he desires. This is very important in supervisory control where the dispatchers after they obtain control of the unit often find it desirable to perform a plurality of operations with said unit in rapid succession. 95

By making the proper selection the selecting relay 403 is energized and the meter 486 is connected to the control line 183 and then to the receiver 115. In this manner remote metering is obtained.

It will be evident from the description above that the system described incorporates all of the direct control obtainable in the synchronous supervisory control systems with the protecting features of the code system and the simplicity and cheapness of the telegraph typewriter system. Although I have disclosed my invention in connection with the supervisory control system, it is obvious that it has applications in any selective signalling system and I do not intend to limit myself of the specific modification described; but, only in so far as set forth in the appended claims.

I claim as my invention:

1. In a signalling system, a first station, a second station, a continuously operating distributor at each of said stations, apparatus units at said second stations, means including said continuously operating distributors for selecting one of said apparatus units for operation, means for identifying said selection at said first station, and means operative only if said identification checks with the selection intended for completing an operating circuit to operate said selected apparatus unit.

2. In a signalling system, a first station, a second station, rotating distributors at each of said stations, apparatus units at said

- second station, a signalling line connecting said stations, means including one of said distributors at said first station for transmitting code combinations of impulses over said signalling line, means including said distributor and arranged to operate following the operation of said code combination of impulses for switching said signalling line to an operative position, means including
- 5 10 one of said distributors at said second station responsive to said code combination of impulses at said second station for conditioning one of said apparatus unit for operation, means including said distributor operative following the complete reception of said code for switching said signalling line to an operative position, means including said signalling line for thereafter operating said apparatus unit directly from said first
- 15 20 station over said signalling line, a supervisory line connecting said stations, means including another of said distributors at said second station for transmitting code combinations of impulses over said supervisory line, means including another of said distributors at said first station responsive to said code combination of impulses for conditioning one of said signalling devices individual to said unit for operation, means including said other distributors at each of said stations, operative following the complete transmission of said code combination of impulses for switching said supervisory line to its operative position, and means including said supervisory line for transmitting a supervisory impulse individual to said operated apparatus unit.
- 25 30 3. In a signalling system, a first station, a second station, continuously operated distributors at said stations, apparatus units at said second station, a signalling line connecting said stations, means including said distributor at said first station for transmitting code combinations of impulses to select an apparatus unit at said second station, means including said distributor at said second station responsive to said code combination of impulses for conditioning one of said apparatus units for operation, and means
- 35 40 45 whereby said signalling line is alternately employed for transmitting said code combinations of impulses and for transmitting operating impulses to operate the selected apparatus unit.
- 50 55 4. In a signalling system, a first station, a second station, apparatus units at said second station, signalling devices individual thereto at said first station, continuously operated distributors at each of said stations, a signalling line connecting said stations, means including one of said distributors at said first station for transmitting code combinations of impulses to said second station, means including one of said distributors at said second station responsive

5 10 15 20 25 30 35 40 45 50 55 60 65 70 75 80 85 90 95 100 105 110 115 120 125 130 to said code combinations for conditioning one of said apparatus units for operation, means including other of said distributors at said second station for transmitting code combinations of impulses from said second to said first station indicative of said selection, means including other of said distributors at said first station for conditioning one of said signalling devices individual to said apparatus unit at said first station for operation, means whereby said control line is employed to transmit both said code combination of impulses for selecting a unit for operation and to transmit the control operating impulse, and means whereby the supervisory line is employed to transmit both said code combination of supervisory signals for selecting the signalling device and the operating supervisory signal.

5. In a control system, a first station, a second station, a line connecting said stations, devices at the second station to be operated from the first station over said line and normally disconnected therefrom, a distributor at each station, means for continuously operating the distributors in synchronism with each other, means at the first station including the distributor thereat for transmitting code combinations of impulses to the second station, each combination being individual to one of the devices, means at the second station including the distributor thereat responsive to said code combinations of impulses for selecting the device individual to the combination and connecting it to the line indefinitely, means for at will operating the selected unit over said line from said first station and means for disconnecting at will from the first station the device from said line.

6. In a control system, a first station, a second station, a plurality of apparatus units at the second station, each of said units being operable to a plurality of positions, a code-operated selecting device at the second station, continuously-rotating distributors at said stations, a line connecting the stations, means including the distributor at the first station for transmitting a code over said line to the second station, said second station distributor being disposed to receive and distribute said impulses of the code to the selecting device to effect a selection of the desired apparatus unit and a connection of it to the line, and means for thereafter operating the selected unit from the first station from one to another of its positions as often as desired.

7. In a control system, a first station, a second station, a signalling line connecting said stations, apparatus units at the second station, a rotating distributor at each station, means for continuously operating the distributors in synchronism, means including the distributor at the first station and the sig-

signalling line for transmitting a code of impulses to the second station, a selector at said second station responsive to said code for selecting one of the apparatus units for operation, said rotating distributor at the second station being disposed to distribute said impulses to the selector to effect a selecting operation and means operable after the selection has been effected for directly connecting the selected apparatus unit to the signalling line whereby direct control of said selected apparatus unit is obtained.

8. In a control system, a first station, a second station, a signalling line connecting said stations, a continuously-rotating distributor at each station, means for causing said distributors to operate in synchronous relation, a selector at the second station, means including the distributor at said first station for transmitting a combination of impulses to said second station, means including the distributor at said second station for distributing the impulses to the selector, and means for thereafter rendering the selector unresponsive to further impulses until the previously set up selection is restored to normal.

9. In a control system, a first station, a second station, apparatus units and a metering device at the second station, a receiving device at the first station, a line connecting the stations, a distributor at each of said stations, means for continuously operating the distributors in synchronous relation means including the distributor at the first station for transmitting code combinations of impulses over the line, code-operated means including the distributor at the second station for selecting any one of said units from the first station, said code operated means being operable to select the meter device, means including the distributors at both stations operative following the complete selecting operation for directly connecting the receiving device and the metering device through the line, and means at the first station for effecting the disconnection of said devices from the line at will.

10. In a control system, a first station and a second station, a receiver device at the first station, a current-operated meter device and apparatus units at the second station, a line connecting the stations, a distributor at each station, means for effecting continuous synchronous operation of the distributors, means at the first station including the distributor thereat for transmitting code combinations of impulses to the second station individual to said meter device and apparatus units, code-operated means at the second station including the distributor thereat for selecting one of said apparatus units at the second station, and means whereby said selecting means associates said receiver device with the meter device and the line.

11. In a supervisory control system, a first station, a second station, a line connecting said stations, apparatus units at said second station, means including a continuously-operating distributor for transmitting code combinations of impulses over said line from said first to said second station, means including a continuously-operating distributor at said second station responsive to said code combination of impulses for selecting one of said units for operation, and means including said distributors for providing a direct electrical connection between said selected unit and said first station over said line.

12. In a signaling system, a first station, a second station, a control line connecting said stations, apparatus units at said second station, operating means at the first station, continuously-rotating distributors at each of said stations, means including said continuously-rotating distributors for selecting said apparatus units for operation from said first station by means of code combinations of impulses transmitted over said line, and switching relays at said stations controlled by the distributors for switching the control line into connection with the selected unit and the operating means at the first station whereby said units, when selected, are maintained indefinitely under direct control from said first station.

In testimony whereof, I have hereunto subscribed my name this 27th day of May, 1926.

THOMAS U. WHITE.
